YARN WINDING DEVICE

Albert W. Keight, Cumberland, Md., assignor to
Celanese Corporation of America, a corpora-
tion of Delaware

Application July 22, 1948, Serial No. 40,100

6 Claims. (Cl. 242—43.6)

1

This invention relates to the winding of yarns into packages, and relates more particularly to a novel traversing mechanism adapted to be employed in connection with yarn twisting and winding apparatus whereby double-tapered yarn packages may be wound without the necessity for giving reciprocating motion to the revolving spindle upon which the yarn package support rests.

Double-tapered yarn packages have heretofore been formed by superimposing two motions on the guide directing the yarn on to the bobbin, namely, an up and down traversing or chasing motion and a slow progressive feed or lift for building the package. The progressive feed or lift usually moves only once during the filling of the bobbin or yarn package support. Yarn packages wound in this manner cannot be dressed economically to remove any soiled yarn on the bottom layers of the package since the removal of the bottom layers necessitates complete back winding to clean up the yarn. Certain mechanisms have been provided for superimposing a builder motion on the normal chaser or traverse motion wherein the spindle is moved. However, these mechanisms are of a considerable degree of complexity and present appreciable servicing and adjustment difficulties.

It is, therefore, an important object of this invention to provide novel means of a simple yet efficient design adapted to cooperate with the ring rail of a ring twisting and winding device for producing a traverse stroke having a builder motion superimposed thereon so as to enable satisfactory yarn packages of a double-tapered cone shape to be wound.

Another object of this invention is the provision of means comprising a traverse mechanism for a twisting and winding device having a plurality of reciprocating ring rails wherein the use of counterbalancing weights is eliminated.

Other objects of this invention, together with certain details of construction and combinations of parts, will appear from the following detailed description and the accompanying drawing.

In the drawing wherein a preferred form of my invention is shown, the figure is a perspective view of a winding and twisting device embodying my invention, certain conventional elements being omitted from the figure in the interest of clarity.

Like reference numerals indicate like parts throughout the drawing.

Referring now to the drawing, yarns 1, coming from any suitable source of supply, such as

2

a metier or spinning cabinet (not shown), pass downwardly and are threaded through travelers 2 each mounted on spinning rings 3 suitably attached to ring rails 4 and 5. The ring rails 5 each carry a plurality of spinning rings 3 suitably spaced thereon so that multiple winding operations may be carried on. Yarns 1, after passing through travelers 2, are each taken up on rotating bobbins 6 and 7. The bobbins are seated on driven spindles of conventional construction (not shown), which are rotated at high speed in the usual manner, as by a belt or belts engaging the whorl of the spindles. The rotation of bobbins 6 and 7 forms a plurality of yarn packages, the yarn windings 8 of which are suitably distributed along the barrel of the several bobbins 6 and 7 by a vertical reciprocating traverse or chaser motion imparted to ring rails 4 and 5. The vertical reciprocation of ring rail 4 is counterbalanced by the reciprocation of ring rail 5 which is operatively connected thereto in a manner which will hereinafter be described in detail. The traverse or chaser motion of each of ring rails 4 and 5 is imparted thereto by the rotation of heart-shaped cam 9 keyed to a cam shaft 10 which is driven by suitable means (not shown). The cam 9 acts on a cam follower 11 rotatably mounted on a pin 12 carried in a rocker arm 13 which is pivotally mounted at 14 by means of any suitable element attached to the machine frame (not shown). The upper end of rocker arm 13 is provided with a slot 16 having a pin 17 set therein to which are attached traverse chains or cables 18. Traverse cables 18 are trained around pulleys 19 which are fixed to a pin 20 carried by a rocker arm 21 which is bifurcated to form fingers 22 in which the pin 20 is rotatably mounted. Rocker arm 21 is pivoted at 23 in any suitable manner. Pin 20 also acts as a cam follower for an auxiliary cam 24 keyed to a driven shaft 25 which is geared to main cam shaft 10 through a suitable gear reduction device (not shown). The functions of auxiliary cam 24 will be described hereinafter in detail.

The traverse cables 18 are anchored at their opposite ends in a clamp 26 mounted on parallel rods 27 and 28 as by set screws 29. Parallel rods 27 and 28 are slidably mounted in suitable guide bearings (not shown). Mounted on rod 28 are a plurality of brackets 30 and 31, brackets 30 being fixed thereto by said screws 32 and brackets 31 being fixed to said rod by set screws 33. Anchored in brackets 30 are cables 34 which are trained over rotatably mounted pulleys 35 and are attached to feet 36 carried by lifter

rods 37 which are fixed to ring rail 4. A pair of cables 38 are anchored at one end in brackets 31, are trained over rotatably mounted pulleys 39 and are attached to feet 40 carried by lifter rods 41 which are fixed to ring rail 5.

The rotation of heart-shaped cam 9 which is driven by main camshaft 10 cooperates with cam follower 11 to cause arm 13 to be rocked about pivot 14. When the rotation of cam 9 causes arm 13 to move to the right, for example, as shown in the drawing, traverse cables 18 cause clamp 26 together with parallel rods 27 and 28 to be moved to the left. Since brackets 30 are fixed to rod 28, these brackets will also move to the left and cause cables 34 to raise feet 36 and 15 lifter rods 37. This action raises ring rail 4 and the distance through which it rises constitutes the upward traverse stroke of ring rail 4 which distributes windings 8 on bobbin 6. Since brackets 31 are also simultaneously drawn to the left, cables 38 allow feet 40 and lifter rods 41 to fall and to lower ring rail 5 a distance equal to the distance through which ring rail 4 rises. This motion constitutes the downward traverse stroke of ring rail 5 and distributes windings 8 on bobbin 7. Since ring rails 4 and 5 are in a counterbalanced relationship further rotation of cam 9 allows rocker arm 13 to reverse its movement thus allowing ring rail 4 to fall and execute the downward ring rail traverse stroke while ring rail 5 simultaneously rises to execute its upward traverse stroke. Each traverse stroke is uniform and the distance through which counterbalanced ring rails 4 and 5 move is fixed by the periphery of cam 9.

Without a suitable builder motion superimposed on the traverse motion of ring rails 4 and 5 described above, the yarn windings form a yarn package of cylindrical shape. Such a package is quite undesirable since the traversing of the heavy ring rails cannot be effected with enough speed to yield a yarn package having windings which are angled sufficiently to produce a coherent and compact package wherein the yarn windings resist sloughing off or turning at the ends. Thus, it is necessary that the path of the traverse stroke produced by the rotation of cam 9 be progressively advanced up and down bobbins 6 and 7 by a suitable builder motion so that a double-tapered yarn package having windings so distributed that a package of satisfactory physical characteristics may be formed.

The desired builder motion is produced by the rotation of cam 24 which is mounted on and rotated by camshaft 25, which is suitably geared to camshaft 10 through a gear reduction device, as indicated above. Cam 24 is rotated at but a fraction of the speed at which cam 9 is rotated. Thus, as cam 24 slowly rotates in contact with cam follower pin 20, it slowly rocks auxiliary rocker arm 21 about pivot 23. This motion gradually increases and decreases the distance between pulleys 19 and pin 17 in rocker arm 13 and thus increases and decreases the effective length of traverse cables 18 therebetween. As the effective length of traverse cables 18 between pulleys 19 and pin 17 is gradually increased, the uniform traverse stroke of ring rails 4 and 5 imparted by the rotation of cam 9 is gradually advanced upward along bobbin 6 and downward along bobbin 7. Conversely, when the effective distance between pulleys 19 and pin 17 is gradually decreased by the rotation of cam 24, the uniform traverse stroke of ring rail 4 is gradually lowered along bobbin 6 and gradually raised along bobbin 7.

My novel apparatus builds a very desirable double-tapered yarn package without employing a traversing spindle and without any complex gearing. Since ring rails 4 and 5 are so arranged as to counterbalance each other, the problem of deadweight is satisfactorily eliminated, thus permitting a fairly rapid traverse stroke.

It is to be understood that the foregoing detailed description is given merely by way of illustration and that many variations may be made therein without departing from the spirit of my invention.

Having described my invention, what I desire to secure by Letters Patent is:

1. In a device for producing yarn packages, the combination with rotating yarn supports and a pair of countermoving ring rails for winding yarn onto said yarn supports, of means for traversing each of said ring rails in opposed, counterbalanced relationship to produce a chaser motion with a traverse stroke of uniform length, and means for superimposing a builder motion alternating in direction on each of said chaser motions, so that the path of the uniform traverse stroke of one ring rail relative to a yarn support is progressively raised while the path of the uniform traverse stroke of the other ring rail relative to a yarn support is simultaneously and progressively lowered.

2. In a device for producing yarn packages, the combination with rotating yarn supports and a pair of countermoving ring rails for winding yarn onto said yarn supports, of means including a driven transverse cam and a pivoted rocker arm cooperating therewith operatively connected to said ring rails for traversing each of said ring rails in opposed, counterbalanced relationship to produce a chaser motion with a traverse stroke of uniform length, and means including a second cam rotating in timed relationship with the traverse cam and cooperating with a cam follower operatively connected to the ring rails and adapted to be moved by the second cam toward and away from the pivoted rocker arm for superimposing a builder motion alternating in direction on each of said chaser motions, so that the path of the uniform traverse stroke of one ring rail relative to a yarn support is progressively raised while the path of the uniform traverse stroke of the other ring rail relative to a yarn support is simultaneously and progressively lowered.

3. In a device for producing yarn packages, the combination with rotating yarn supports and a pair of countermoving ring rails for winding yarn onto said yarn supports, of means for traversing each of said ring rails in opposed, counterbalanced relationship to produce a chaser motion with a traverse stroke of uniform length including a driven transverse cam and a pivoted rocker arm cooperating therewith connected to said ring rails by flexible traverse cable means anchored at one end in said rocker arm, and means for superimposing a builder motion alternating in direction on each of said chaser motions including a second cam rotating in timed relationship with the traverse cam and cooperating with a cam follower carrying a pulley around which the flexible traverse cable means pass, which cam follower and pulley are adapted to be moved by the second cam toward and away from the pivoted rocker arm whereby the mean distance between said pivoted rocker arm and pulley is progressively decreased and increased so that the path of the uniform traverse stroke

of one ring rail relative to a yarn support is progressively raised while the path of the uniform traverse stroke of the other ring rail relative to a yarn support is simultaneously and progressively lowered.

4. In a device for producing yarn packages, the combination with rotating yarn supports and a pair of countermoving ring rails for winding yarn onto said yarn supports, of means for traversing each of said ring rails in opposed, counterbalanced relationship to produce a chaser motion with a traverse stroke of uniform length including a driven traverse cam and a pivoted rocker arm cooperating therewith connected to said ring rails by flexible traverse cable means anchored at one end in said rocker arm and at the other end in a clamp adjustably fixed to at least one reciprocating, slidably mounted rod operatively connected to the ring rails, and means for superimposing a builder motion alternating in direction on each of said chaser motions including a second cam rotating in timed relationship with the traverse cam and cooperating with a cam follower carrying a pulley around which the flexible traverse cable means are trained, which cam follower and pulley are adapted to be moved by the second cam toward and away from the pivoted rocker arm whereby the mean distance between said pivoted rocker arm and pulley is progressively decreased and increased so that the path of the uniform traverse stroke of one ring rail relative to a yarn support is progressively raised while the path of the uniform traverse stroke of the other ring rail relative to a yarn support is simultaneously and progressively lowered.

5. In a device for producing yarn packages the combination with rotating yarn supports and a pair of countermoving ring rails for winding yarn onto said yarn supports, of means for traversing each of said ring rails in opposed, counterbalanced relationship to produce a chaser motion with a traverse stroke of uniform length including a driven traverse cam and a pivoted rocker arm cooperating therewith connected to said ring rails by flexible traverse cable means anchored at one end in said rocker arm and at the other end in a clamp adjustably fixed to at least one reciprocating, slidably mounted rod, brackets adjustably mounted on one of said reciprocating rods, and flexible lifter means connecting said brackets to ring rail lifter rods, and means for superimposing a builder motion alternating in direction on each of said chaser motions including a second cam rotating in timed relationship with the traverse cam and cooperating with a cam follower carrying a pulley around which the flexible traverse cable means are trained, which cam follower and pulley are adapted to be moved by the second cam toward and away from the pivoted rocker arm whereby

the mean distance between said pivoted rocker arm and pulley is progressively decreased and increased so that the path of the uniform traverse stroke of one ring rail relative to a yarn support is progressively raised while the path of the uniform traverse stroke of the other ring rail relative to a yarn support is simultaneously and progressively lowered.

6. In a device for producing yarn packages, the combination with rotating yarn supports and a pair of countermoving ring rails for winding yarn onto said yarn supports, of means for traversing each of said ring rails in opposed, counterbalanced relationship, wherein one ring rail rises as the other falls to produce a chaser motion with a traverse stroke of uniform length including a driven traverse cam and a pivoted rocker arm cooperating therewith connected to said ring rails by flexible traverse cable means anchored at one end in said rocker arm and at the other end in a clamp adjustably fixed to at least one reciprocating, slidably mounted rod, brackets adjustably mounted on one of said reciprocating rods and flexible lifter means passing over pulleys connecting said brackets to ring rail lifter rods, and means for superimposing a builder motion alternating in direction on each of said chaser motions including a second cam rotating in timed relationship with the traverse cam and cooperating with a cam follower carrying a pulley around which the flexible traverse cable means are trained, which cam follower and pulley are adapted to be moved by the second cam toward and away from the pivoted rocker arm whereby the mean distance between said pivoted rocker arm and pulley is progressively decreased and increased so that the path of the uniform traverse stroke of one ring rail relative to a yarn support is progressively raised while the path of the uniform traverse stroke of the other ring rail relative to a yarn support is simultaneously and progressively lowered.
